UNITED STATES PATENT OFFICE.

JOHN WILSON BROWN, JR., OF PHILADELPHIA, PENNSYLVANIA.

DESIGN FOR A MEAT-CHOPPER FEED-SCREW.

SPECIFICATION forming part of Design No. 31,310, dated August 1, 1899.

Application filed June 6, 1899. Serial No. 719,612. Term of patent 14 years.

To all whom it may concern:

Be it known that I, JOHN WILSON BROWN, Jr., a citizen of the United States, residing in Philadelphia, Pennsylvania, have invented and produced a new and original Design for Meat-Chopper Feed-Screws, of which the following is a specification.

My design for a feed-screw for meat-choppers is clearly illustrated in the accompanying drawing, the figure of which is a side view of the screw.

The essential feature of the design is the screw, substantially as shown in the accompanying drawing.

15 A is the body of the feed-screw, having the threads as indicated in the drawing. The end a of the feed-screw is tapered, as shown,

and at the rear of the feed-screw is a flange b. Extending from the rear end of the feed-screw is a projection d, and extending from the forward end of the feed-screw is a projection d'.

I claim—

The design for a feed-screw of a meat-chopper as herein described and as shown in the accompanying drawing.

In testimony whereof I have signed my name to this specification in the presence of two subscribing witnesses.

JOHN WILSON BROWN, JR.

Witnesses:

H. F. REARDON,
F. E. BECHTOLD.
